[57] CLAIM

The ornamental design for a baseball glove, as shown.

DESCRIPTION

FIG. 1 is a rear elevational view of a baseball glove showing my new design;
FIG. 2 is a front elevational view thereof;
FIG. 3 is a top plan view thereof;
FIG. 4 is a bottom plan view thereof;
FIG. 5 is a little finger-side elevational view thereof;
FIG. 6 is a thumb-side elevational view thereof; and
FIG. 7 is a longitudinal cross-sectional view thereof, taken substantially on line 7—7 of FIG. 1.
